UNITED STATES PATENT OFFICE

1,978,937

CASH REGISTER

Charles W. Green, Ilion, N. Y., assignor, by mesne assignments, to The National Cash Register Company, Dayton, Ohio, a corporation of Maryland

Application August 31, 1931, Serial No. 560,324

12 Claims. (Cl. 235—130)

This invention relates to cash registers and like machines and particularly to adding, transferring and printing devices for said machines.

The particular embodiment of the invention herein illustrated is adapted to be applied to machines of the type disclosed in the patent of Frederick L. Fuller, No. 1,742,701 issued January 7, 1930, but it is to be understood that the invention is applicable to machines of very different construction.

The said patent shows two totalizers across one of which, the printing platen must move to reach the position for printing a total from the other totalizer. In so moving, the platen or associated parts may catch on the totalizer wheels and disturb the setting. It is the object of this invention to obviate such possibility by providing means whereby the totalizer wheels automatically will be locked against rotation during total printing operations.

Referring to the drawings attached hereto:

Fig. 1 is a cross sectional view showing the keys and the main actuating mechanism.

Fig. 2 is a detail view of the printing device in normal position.

Fig. 3 is a cross sectional view on the line 3—3 of Fig. 4 showing the parts in total printing position.

Fig. 4 is a cross section on the line 4—4 of Fig. 2, showing the transfer actuating mechanism.

Fig. 5 is a detail perspective view of the locking device.

Referring to Fig. 1, the usual keys 10 are mounted on a shaft 11. The rearward ends 12 of the keys each have an upwardly extending lug 13, the forward face of which is notched at 14 to receive a tongue 15 on the usual key coupler 16. This key coupler is mounted to swing about a shaft 17. Its free end rests on the key bars 12 and when the bars are swung upwardly the coupler swings with them. The key coupler carries at one end a pin 18 which is received in a horizontal slot 19 in a member 20. The member 20 is accordingly reciprocated vertically upon the operation of any key.

The lower end of member 20 is slotted at 21 to receive a guide pin 22 fixed on the frame, 50 and its upper end is bifurcated to provide arms 23 each of which carries a rack 24. These racks alternately mesh with a pinion (not shown) on a shaft 25. This particular mechanism is well known and is shown in full in the above mentioned patent. The effect of the mechanism

thus far described is to produce a full rotation of shaft 25 on each operation of any key. The shaft 25 carries cams 26 for sequential operation of the totalizer transfer pawls, as will be more fully described hereafter.

Centrally of the machine is a shaft 100 on which are mounted for free rocking movement certain segmental racks 101. These racks 101 are suitably secured to certain groups of cam plates 102, there being a block of these cam plates for each denominational series of keys, as cents, dimes, dollars, etc. The cam plates of each block are differentially slotted as shown at 103 and the slot of each plate receives a pin 104 affixed to the end of an arm 105, integral with and extending upward from one of the key levers. This mechanism is well known in the art and is fully described in the above mentioned patent. It will be obvious from Fig. 1, that if a key 10 be depressed, its arm 105, by the co-action of the pin 104 and the slot 103, will rock the group of cam plates upwardly to an extent dependent upon the length and inclination of the particular slot 103. This will result in a proportional movement of the segmental rack 101 attached to the group of cam plates.

Printing wheels 200 and totalizers 200A and 200B are arranged on an arc concentric with shaft 100. The printing wheels 200 each carry a pinion 200', in constant mesh with a segmental rack 101. As a result, upon the operation of any key, the printing wheel is appropriately set for printing a figure corresponding to the key or keys depressed.

The totalizers are identical and are fully described in the patent to C. W. Green, No. 1,793,795 dated February 24, 1931. Only so much of the totalizer structure will be described as is essential to an understanding of the present invention.

Referring to Figs. 1, 3 and 4, the totalizers 200A and 200B are mounted to rock about certain shafts 201 and 202, the shafts being mounted in certain frame members 503 and 504. The following description relates only to the upper totalizer 200A, which comprises a series of printing wheels 210 each affixed to a pinion 203, all co-axially mounted on a shaft 204. The shaft 204 is mounted in a frame 207 which frame rocks about the shaft 201. This rocking movement, as fully set forth in the above mentioned patent to C. W. Green, serves to bring the pinions of the totalizer wheels into mesh with the rack 101 in order to obtain

an entry into the totalizer of an amount corresponding to the key depressed.

Transfers are effected by means of an arm 205 slotted to receive the shaft 201. At its upper end the arm 205 carries a pawl 206 which engages the pinion 203 of one of the totalizer wheels. At its lower end, the transfer arm 205 has a cam slot 208 to receive a pin 209. The pin 209 is mounted on an arm 220, which 10 arm is rockably mounted on the shaft 100. The arm 220 is provided with an upwardly extending lug 221 to which is attached one end of a spring 222. It will be understood that there is an arm 220 and a spring 222 for each transfer pawl. This is clearly shown in Fig. 4.

The arms 220 extend rearwardly of the shaft 105 and at their extremities carry follower pins 223 which engage the cams 26 on shaft 25.

As a key is depressed the segmental racks 101 20 are moved differentially to set up the amount on the printing wheels 200. The appropriate totalizer at the same time is rocked into engagement with the racks and receives an entry of the amount. When the key reaches the bottom of its down stroke, item printing occurs, the totalizer is disengaged from the racks, and the cams 26 have been rotated 180° from the position shown in Fig. 1. As the keys move up again, the cams complete their rotation, moving seriatim under the pins 223 of the transfer arms 220. The cams raise the rearward ends of the arms, rocking them about the shaft 100, and thus actuating the transfer pawls 205. As each follower pin 223 rides over its cam 26, 30 the spring 222 returns the transfer arm to normal position.

When it is desired to print a total from either of the totalizers, the mechanism described hereafter is employed. Only so much of this mechanism will be described as is essential to an understanding of the instant invention, and reference is made to the above cited patent to F. L. Fuller for further details.

The printing mechanism, comprising a supply of paper, a receiving reel, feeding means, a printing platen, and the inking ribbon mechanism, is built as a unit so as to be readily detachable. The printer parts are carried by a frame which is pivotally mounted on the segment shaft 100 and can be swung with this shaft as a center so that the printing platen may overlie the detail printer or the A or B counters, as desired.

The printer comprises side plates 400 and 401 55 provided with claws 400' for engaging over the segment shaft 100. The side plates are connected by a back bar 402 and by tie rods 403 and 404. Extending transversely between the side plates is a platen shaft 406 upon which is supported a platen 407 by means of two arms 408 and 409 (Figs. 2 and 3). Extending rearwardly beyond the platen shaft is a platen tail 411 which is actuated by a hammer for forcing the platen against the type.

The paper rolls and paper feed mechanism are carried in a separate frame pivoted to the side plate 400 on a stud shaft 415. This frame comprises a U-shaped plate 416 which carries a storage roll 417 and a supply roll 418. The paper is fed over suitable rollers 419, 420, 421, 422, 423 and 424, so as to pass over the platen 407. The mechanism for so feeding the paper is fully disclosed in the said patent to F. L. Fuller.

For ordinary item printing, the parts are in

the position of Fig. 2, and the platen is operated by linkage which is actuated by a cam 429 on the shaft 25. This cam also actuates the paper feed.

A handle 440B is formed on the side plate 401 for rocking the printer frame about the segment shaft 100. When the frame is so rocked, the platen moves over the printing wheels 200 and also over the totalizer 200A and occupies a printing position over the totalizer 200B. The rocking movement of the printer frame is utilized to actuate the platen, which operates when it is over the totalizer 200B.

A second handle 440A is provided. This handle is formed on a lever 441 which is mounted on a horizontal shaft 442 journaled in the side plates 400 and 401. The lever is connected to certain platen operating mechanism disclosed in the patent to F. L. Fuller. An arm 443 projecting forwardly from the lever 441 carries a lug 444 for cooperation with either of two cam grooves 500 or 501 (Fig. 3), formed in the totalizer supporting frame 504.

If the handle 440B be operated, the lug 444 will enter the groove 500. The groove is eccentric to the shaft 100, hence will move the lever 441 and actuate the platen. If, on the other hand, the handle 440A be operated, the lug 444 will enter the groove 501. This groove is shorter and more eccentric with respect to the shaft 100 than is the upper groove 500. Hence the platen will be operated sooner in the course of the rocking movement of the printer frame and printing will take place when the platen is over the upper totalizer 200A.

It will be noted that in total printing operations, the platen must be moved across the printing surface of the totalizer wheels. Particularly is this the case when the total is taken from the lower totalizer 200B. Due to the fact that the usual inking ribbon forms the surface adjacent the totalizer, there is danger of the ribbon or ribbon guide catching on the surface of one of the totalizer wheels and disturbing the setting thereof as the platen moves across.

In order to obviate this danger, the following mechanism has been devised.

A plate 300 (Fig. 5) has upturned ends 301 and 302, through which the shaft 25 passes and is free to rotate.

Above the shaft 25, the right-hand end 301 of the plate is provided with an abrupt cam surface 303, merging into a surface 304 formed on a laterally projecting arm 305. The latter surface (304) is so formed that when rocked to the position of Fig. 3, it is concentric with the shaft 100.

The other end (302) of the plate is provided, above the shaft 25, with a rod 306 extending outwardly and parallel with the shaft 25.

As shown in Fig. 4, the rod 306 lies at the rear of the transfer pawl actuating arms 220. If the rod 306 be rocked forwardly, it will rock the arms 220. These, in turn, will tilt the transfer arms 205 (Fig. 3) and bring their pawls 206 into engagement with the totalizer pinions 203, locking the latter against rotation.

Mounted on the side plate 400 of the printing frame is a pin 310 projecting toward the plate 300 and parallel to the shaft 25. This pin is so placed that when the printing frame is in normal position, i. e., for item printing operations, it lies just to the rear of the abrupt cam surface 303. This allows the rod 306 to remain clear of the arms 220 so as not to interfere with ordi-

nary accumulating and transferring operations. In this position the end 302 of the plate 300 rests against a fixed stop 311 secured to the totalizer supporting frame (Fig. 4).

5 Upon any rocking movement of the printer frame the pin 310 acts upon the abrupt cam surface 303 to rock the end 301 around the shaft 25. This, of course, rocks the rod 306 in the same direction. The rod 306 rocks the arms 10 220, locking the totalizer wheels as previously described. When locked, the parts are in the position shown in Fig. 3.

The portion of the arm 220 against which the rod 306 acts is best shown in Fig. 1. In normal position, the rod 306 is adjacent an inclined surface 220' on the arm 220. As the parts rock from the position of Fig. 1 to that of Fig. 3, the rod 306 rides from the surface 220' to a surface 220'', which, when the arm 220 is in locked position, 20 is concentric with the shaft 25.

It will be noted that the force exerted by the surface 220' against the rod 306 is along a line passing above the shaft 25, while the surface 220'' is shaped so that its force against the rod 25 306 will be along a line passing through the center of shaft 25. As a result, when the shaft 306 engages in the surface 220'', the force just mentioned has no tendency to rotate the rod 306.

30 When the printing frame is rocked back to normal position, the shaft 442 engages an arm 312 on the end 301 of the plate 300 and positively returns the rod 306 to normal position.

It will be noted that regardless of which totalizer is to be engaged with the platen, the amplitude of movement of the rod 306 is the same. The cam surface 303 is, therefore, made only of sufficient extent to produce the desired movement. The remainder of the movement of the pin 310, which movement is necessarily on an arc concentric with the shaft 100, takes place over the concentric surface 304 of the arm 305 without further moving the plate 300. This co-acting of the pin 310 with the concentric surface 304 serves to prevent any release of the totalizers during the return movement of the printer frame until the platen has moved clear of both totalizers.

The form of mechanism herein described is well adapted to fulfill the objects stated, but, it is to be understood that it is intended to confine the invention to the one form of embodiment herein shown, since it may be embodied in various forms, all coming within the scope of the claims which follow.

What is claimed is:—

1. A cash register having a plurality of sets of adjustable type; a platen for co-action with either set; means for producing relative motion between said sets of type and said platen for selection of a desired set; and means for locking said sets against disturbance of their adjustments during such movement.

2. A cash register having a plurality of sets of adjustable type; a platen for co-action with either set; means for producing relative motion between said sets of type and said platen for selection of a desired set; and means actuated by such relative movement for locking said sets of type against disturbance of their adjustments.

3. A cash register having a plurality of totalizers; printing means selectively movable to print from any of said totalizers; and means operated by the selecting movement of said printing

means for locking said totalizers against disturbance of their settings.

4. A cash register having a plurality of aligned totalizers on parallel shafts; printing means mounted to move transversely of said shafts for selective positioning over any desired totalizer; means for locking said totalizers against movement relative to said shafts, and means carried by said printing means for actuating said locking means upon selecting movement of said printing means.

5. A cash register having a plurality of arcuately arranged totalizers each comprising a series of printing wheels; a platen movable in a similar arc for selective positioning over any desired totalizer, the path of the platen being tangential to the totalizer wheels; and means operated by selecting movement of the platen for locking the totalizer wheels against rotation.

6. A cash register having a plurality of arcuately arranged totalizers on parallel shafts; transfer pawls for said totalizers; common actuating means for the transfer pawls of each denomination of the several totalizers; a frame mounted to swing concentrically of said totalizers; a platen carried by said frame and swingable therewith to printing position over any of the totalizers; a bar adapted to move the actuating means for the transfer pawls so as to press the transfer pawls into locking engagement with the totalizers; and means carried by said frame for actuating said bar upon swinging movement of said frame.

7. A cash register having a plurality of totalizers each comprising a series of printing wheels; transfer means between the wheels of each totalizer; a plurality of actuating levers for the transfer means, a member common to all of said actuating levers and adapted to move them into a position bringing the transfer means into locking engagement with the totalizer wheels; a platen movable tangentially across said totalizer wheels for selective positioning over any desired totalizer; means connected to said platen for moving said member upon movement of said platen.

8. A cash register having item printing wheels and a plurality of totalizers; each totalizer comprising a series of printing wheels; a platen normally positioned over said item printing wheels; means for moving said platen tangentially of said totalizer wheels for selective positioning over any desired totalizer; means whereby movement of said platen away from said item printing wheels locks said totalizer wheels against rotation; and means whereby the return of said platen over said printing wheels positively releases said totalizer wheels.

9. In a register, a totalizer, transfer mechanism therein including a carrying pawl and an operating means for the pawl, and a locking mechanism for the totalizer, the said locking mechanism arranged to actuate the operating means for the transfer pawl.

10. In a register, a totalizer, transfer mechanism therein, and a locking mechanism for the totalizer, the transfer and locking mechanisms having certain parts in common and capable of different movements, one of said movements causing the parts to assist in transferring, and the other of said movements causing the parts to assist in locking.

11. In a register, totalizer wheels, means to print the amount registered thereon, transfer mechanism to advance the wheels a step during

80

adding operations, locking mechanism acting on the transfer mechanism to lock the wheels against advancement during printing operations, and separate driving means to obtain each of said operations.

12. In a register, printing elements, a pivoted platen adapted to be swung over the printing

elements, a supporting frame for the platen, means to lock the elements against rotation, and means secured to the supporting frame to move the locking means to effective position when the platen is moved toward the printing elements.
